UNITED STATES PATENT OFFICE

171,512

TABLE LAMP

Harry S. Miller, Los Angeles, Calif.

Application August 3, 1953, Serial No. 26,238

Term of patent 3½ years

(Cl. D48—20)

To all whom it may concern:

Be it known that I, Harry S. Miller, a citizen of the United States, residing at 949 Westbourne Drive, Los Angeles, in the county of Los Angeles, State of California, have invented a new, original, and ornamental Design for a Table Lamp, of which the following is a specification, reference being had to the accompanying drawing, forming a part thereof.

Fig. 1 is a perspective view of a table lamp embodying my new design;

Fig. 2 is a side elevational view; and

Fig. 3 is a rear elevational view.

I claim:

The ornamental design for a table lamp, as shown.

HARRY S. MILLER.
